[57] CLAIM

The ornamental design for a baby or toddler knee pad,
as shown and described.

DESCRIPTION

FIG. 1 is a front elevational view of a knee pad for baby
or toddler showing my new design;

FIG. 2 is a rear elevational view thereof;

FIG. 3 is a left side elevational view thereof;

FIG. 4 is a right side elevational view thereof;

FIG. 5 is a top plan view thereof; and,

FIG. 6 is a bottom plan view thereof.

The cross-hatch shading shown in all views is under-
stood to repeat throughout the indicated areas.

*FIG. 1**FIG. 2**FIG. 3*

FIG. 4

FIG. 5

FIG. 6
